UNITED STATES PATENT OFFICE.

WILLIAM L. IMLAY, OF NEW YORK, N. Y.

ELECTRIC-CURRENT ECONOMIZER.

1,126,016.

Specification of Letters Patent. Patented Jan. 26. 1915.

Application filed January 2, 1914. Serial No. 810,036.

To all whom it may concern:

Be it known that I, WILLIAM L. IMLAY, a citizen of the United States, residing at New York, in the county of New York and State of New York, have invented certain new and useful Improvements in Electric-Current Economizers, of which the following is a specification.

My invention relates to improvements in electric current economizers, and more particularly to an improved system of electric distribution in which a distributer is provided connected with a number of consuming circuits, and engaged by a brush in a source circuit, the brush movable into contact with the distributer only upon the attainment of the proper rotary motion of the member carrying the brush.

A further object is to provide a step-down device consisting of a distributer comprising a circular series of contacts adapted to be engaged by a brush carried by a rotary member, and normally out of engagement with the contacts, means being provided which compel the brush to move into engagement with the contacts only after a predetermined speed is attained by the brush carrying member, and which device compels the brush to move away from the contacts when the speed of the brush carrying member diminishes.

A further object is to provide elastic means for normally holding the brush of a device such as above referred to, away from the contacts, the spring being overcome by centrifugal action of pressure of air when the carrying member is revolved at a sufficient speed.

A further object is to provide an improved mechanism of the character stated in which a plurality of consuming circuits may be supplied from a source circuit in such a way as to greatly economize the current, permitting a plurality of lamps, motors, or other devices in the consuming circuits to efficiently operate from a source circuit of a voltage normally used for operating a lesser number of such devices.

With these and other objects in view, the invention consists in certain novel features of construction and combinations and arrangements of parts as will be more fully hereinafter described and pointed out in the claims.

In the accompanying drawings: Figure 1 is a plan view illustrating my improve-

ments. Fig. 2 is a view in section on the line 2—2 of Fig. 1. Fig. 3 is a view in section on the line 3—3 of Fig. 1. Fig. 4 is a perspective view illustrating a modification, 60, and Fig. 5 is a diagrammatic view illustrating a simple form of electric circuits which may be utilized in carrying out my invention.

1 represents a base of non-conducting material and 2 are standards secured on the base and supporting a stationary shaft 3.

4 represents a distributer which structurally resembles the ordinary commutator but operates to distribute the current and not accumulate as does the commutator. This distributer consists of a circular series of contact blocks 5 insulated from each other and from the shaft and secured to a sleeve 6 held against rotary movement on the shaft 75 by means of a set screw 7. A disk 8 is mounted to turn freely on the shaft 3 adjacent one end of the distributer 4, and is provided with a pulley 9 driven by a belt 10 from any source of power.

A sleeve 11 is interposed between the disk 8 and the sleeve 6 and secured by means of a set screw 12. A coiled spring 13 is located around shaft 3 and bears at one end against one of the bearings 14 on a standard 2. The other end of the coiled spring bears against a washer 15 which is located against the pulley 9 and serves to press the disk 8 against sleeve 11.

A brush holder 16 is pivotally supported 90 between its ends on a screw 17 secured to a stud 18 fixed to disk 8 and extending through a sleeve 19 on the brush holder to secure the brush holder in place, yet allow the same a free pivotal movement. A brush 20 is secured in one end of the brush holder, and a slotted arm 21 is provided on the other end of the brush holder into which the free end of a spring 22 projects. This spring 22 is secured at one end in a clamp 23 on the disk 8, and by adjustment of the spring longitudinally in the clamp, its tension may be varied, and I may employ other means for varying the strength or tension of the spring to control the action of the brush holder as 105 will more fully hereinafter appear.

A rod 24 is secured to the brush holder slightly beyond its pivot, and this rod 24 operates as a weight which is thrown out by the centrifugal action of the device to compel the brush to move against the contacts as will be explained. Instead of this rod 24,

I might employ a flat blade 25 as indicated in Fig. 4, which would be operated pneumatically or in other words, by pressure against the air when the disk is revolved to move the brush into engagement with the contacts.

The disk 8 carries an arm 31 which operates to balance the weight of the brush holder. To properly adjust this balance, I provide a slot 32 in the arm 31 and locate a bolt 33 in said slot held by nuts 34 at any position of adjustment. This exact form of balance is of course immaterial as I may use other forms of balance which will insure the best results.

In Fig. 5, I show an electric diagram illustrating my invention. 26 represents a wire connecting the positive pole of the electric source 27 with the brush 20. This connection is made through one of the standards 2 as shown clearly in Fig. 1, the current passing through the standard, through the shaft 3, disk 8, brush holder 16, and brush 20. The negative wire extends from the negative side of the electric source and connects to one pole of each of the lamps 29. The other poles of the lamps are connected by wires 30 with the different contacts 5 of the distributor 4.

While I have illustrated lamps in the consuming circuits, it is of course to be understood that any form of device or apparatus for utilizing the electric current might be in the consuming circuits, and the invention is not limited in this particular.

In operation, as soon as a sufficient speed is imparted to disk 8 to move the brush holder by centrifugal action or air pressure as above explained, the brush 20 will successively close the consuming circuits and the speed will be sufficient to so rapidly close the circuits as to prevent any detection by the eye that the circuits have been opened at all. Until a sufficient speed is attained by the disk, there will be no closing of any of the consuming circuits because the brush 20 will be held out of contact by means of the spring 22. This is of the utmost importance because the source current will be of a considerably greater voltage than is desirable in any of the consuming circuits, hence it would be ruinous to allow the brush to remain in contact for any appreciable length of time with any of the contacts of the distributor. The spring therefore operates to prevent any such contact, while the disk is at a stand still, or while running at a low speed, because as soon as the speed is diminished, the spring operates to overcome the centrifugal force and move the brush away from the distributor.

My invention is not limited to any particular use, but is adapted for use as a current economizer in a great many ways, nor is my invention limited to the specific details

of construction illustrated, but I consider myself at liberty to make such changes and alterations as fairly fall within the spirit and scope of the appended claims.

Having thus described my invention, what I claim as new and desire to secure by Letters Patent is:

1. The combination with a distributor, of a contact member movable around the distributor and normally spaced therefrom, and means operated by the rotary movement of the contact member to move the contact into engagement with the distributor when said member attains a pre-determined speed, substantially as described.

2. The combination with a distributor, of a rotary member, a brush holder on said member carrying a brush and having means normally holding the brush out of contact with the distributor, and means operated by the rotary movement of the said member, whereby the brush is moved into contact with the distributor when said member attains a pre-determined speed, substantially as described.

3. The combination with a distributor, of a rotary member, a brush holder pivotally connected to the member, and having at one end a brush normally out of contact with the distributor, and means operated by the rotary movement of the member for moving the brush into contact with the distributor, substantially as described.

4. The combination with a distributor, of a rotary member, a brush holder pivotally connected to the member, and having at one end a brush normally out of contact with the distributor, and a device connected to the brush holder and operated by centrifugal action to move the brush into contact with the distributor, substantially as described.

5. The combination with a distributor, of a rotary member, a brush carried by the rotary member, a spring normally holding the brush out of contact with the distributor, and means operated by the rotary movement of the member for overcoming the spring and moving the spring into contact with the distributor, substantially as described.

6. The combination with a distributor, of a rotary member, a brush carried by the rotary member, a spring normally holding the brush out of contact with the distributor, and a device connected to and movable with the brush, said device thrown outwardly by the rotary movement of the member to overcome the spring and move the brush into contact with the distributor, substantially as described.

7. The combination with a distributor, of a rotary member, a brush holder pivoted between its ends to the rotary member and carrying a brush at one end, a spring connected to the member and engaging the brush holder normally holding the brush

out of contact with the distributor, and means connected to the brush holder and adapted to be operated by the centrifugal action of the member to overcome the spring 5 and move the brush into contact with the distributor, substantially as described.

8. The combination with a distributor, of a rotary member, a brush holder pivoted between its ends to the rotary member and carrying a brush at one end, said brush holder having a slotted arm at its other end, a spring secured to the rotary member, and its free end engaging in the slotted arm normally holding the brush away from the distributor, and a rod secured to the brush holder and adapted to be moved by the centrifugal action of the member to overcome the spring and move the brush into contact with the distributor, substantially as described. 15

9. The combination with a distributor comprising a circular series of contacts, of 20

a rotary member, a brush on said rotary member normally spaced from the contacts of the distributor, said brush connected to 25 the positive side of a source current, a series of electrically operated devices having their negative poles connected to the negative side of the source current, and their positive poles connected to the respective contacts of the 30 distributor, and means operated by the rotary movement of said member for moving the brush into engagement with the contacts of the distributor when the rotary member attains a pre-determined speed, substantially as described. 35

In testimony whereof I have signed my name to this specification in the presence of two subscribing witnesses.

WILLIAM L. IMLAY.
